WIRES TERMINAL

David W. Johnson, New Britain, Conn., assignor
to The Arrow-Hart & Hegeman Electric Com-
pany, Hartford, Conn., a corporation of Con-
necticut

Application February 15, 1939, Serial No. 256,570

3 Claims. (Cl. 173—324)

This invention relates to wire terminals and is usable generally on all types of electrical equipment. More particularly it relates to wire terminals of the type employing a screw to secure a wire to a metal plate, which plate is maintained in place on an insulating base or on the body of an electrical device. Among the conventional means used to secure the terminal plates to the insulating body have been screws, rivets and the like, which were provided expressly for the purpose and which in most cases performed no other function than that of attaching the plate to the body.

It is an object of my invention to make a wire terminal device in which the terminal plate thereof is maintained in place on an insulating block without the use of conventional securing means, or of any especially provided devices for holding the metal terminal to the insulating block.

Another object of my invention is to provide a wiring terminal which—in the absence of, and in elimination of the need for, conventional securing devices—is maintained on an insulating body by the interengagement of the terminal plate and screw with parts of the body.

Other objects and advantages of the invention will become apparent as it is described in connection with the accompanying drawing.

30 In the drawing:

Fig. 1 is a plan view of a wiring terminal device embodying the principles of my invention;

Fig. 2 is a side elevation view of the device illustrated in Fig. 1;

35 Fig. 3 is a section view taken along line 3—3 of Fig. 1;

Fig. 4 is a section view of the invention with the section being taken along line 4—4 of Fig. 2;

40 Fig. 5 is a plan view of the insulating body or block upon which the wire terminal member may be mounted but showing the block with the terminal plate removed;

Fig. 6 is a perspective view of the terminal plate of Figs 1—5;

45 Fig. 7 is a plan view of another form of the invention;

Fig. 8 is a plan view of a modified form of terminal plate.

Referring to the drawing, it will be noted that 50 a wire terminal member 10, which may be stamped from sheet metal in the form of a bar or plate, is mounted upon an insulating body or block 12. The plate 10 is provided with tapped holes into which are threaded binding screws 14 and 16. These terminal screws have relatively

long shanks for the purpose of securing wires of varying thickness to the wire terminal plate 10 and also for the purpose of preventing removal of the terminal plate 10 from the insulating body 12, as will hereinafter be more particularly described. As illustrated, the insulating block or body 12 is provided with a central transverse channel 18 in which the terminal plate 10 is seated. In the bottom of the channel 18 is formed a narrow sub-channel 20 extending from 10 one side of the block partially across the block, in the central portion of the channel 18. In the bottom of the sub-channel 20 there are bored two spaced bores 22 and 24, the bore 24 being at the inner end of the sub-channel 20. The 15 spacing of the bores 22 and 24 is equal to the spacing of the terminal screws 14 and 16 so that the bores may accommodate the ends of the terminal screws when the screws are turned through the terminal plate 10. In diameter, the 20 bores 22 and 24 slightly exceed the diameters of the terminal screws, so that the terminal screws may fit loosely within the bores 22 and 24 without binding. For a similar reason, the width of the sub-channel 20 is equal to or slightly greater 25 than the diameter of the bores 22 and 24.

For the purpose of holding the terminal plate 10 against movement out of the channel in a direction perpendicular to the floor of the channel, there are provided on the side walls of the 30 channel semi-cylindrical extensions 26 terminating above the floor of the channel a distance slightly greater than the thickness of the terminal plate 10. Obviously the semi-cylindrical extensions might take other forms. It is only necessary that there be some extension or protuberance from the side walls of the channel over the top surface of the terminal bar 10 so as to prevent upward movement of the terminal plate 35 out of the channel.

40 From the foregoing, it will be apparent that when the terminal screws 14 and 16 are screwed into the terminal plate so that their shanks extend beneath the terminal plate a less distance than the depth of the sub-channel 20, the terminal bar 10 may be slid longitudinally along the bottom of the channel 18 until the shank of one of the terminal screws strikes against the end of the sub-channel 20 directly over the bore 24. When in this position electric wires may be connected to the terminal device by winding around one or both of the terminal screws 14 and 16. Alternatively, electric wires may be wound around one or both terminal screws before the plate is 45 slid into position. It is much easier to connect 50 55

wires to the device while the plate is removed. The ability to do this is an important advantage of my invention.

The wires may be secured in position by screwing the terminal screws 14 or 16 into the terminal plate until they bind the wires and plates together. The act of screwing these terminal screws 14 and 16 further into the terminal plate than their original position will cause the shank 10 of the screws to take into the bores 24 and 22 so that planar movement of the terminal plate 10 out of the channel will thus be prevented by the shanks engaging the walls of the bores 22 and 24. In this manner, planar movement of the terminal plate 10 longitudinally out of the channel 18 is prevented while at the same time movement of the terminal plate 10 out of the channel 18 in a perpendicular direction is prevented by the engagement of the upper surface of the terminal plate with the protuberances 26. Thus it will be seen that I have provided a novel arrangement of terminal plates and binding screws in association with a mounting block whereby the terminal holds itself in place upon the mounting block without the necessity for the use of any independent or separate securing device, such as a screw or rivet or the like.

Fig. 8 shows a modified form of terminal plate requiring less metal than the plate shown in Fig. 6. In this form of the invention, the extensions 10a and 10b from the sides of the terminal plate will underlie the projections or protuberances such as 26 in the side of the channel 18 and will prevent movement of the terminal plate out of the channel in a perpendicular direction in the same manner as in the case of the modification shown in Figs. 1-6.

In Fig. 7 another form of the invention is shown. In this form the sub-channel 20—1 is enlarged at its inner end portion for manufacturing reasons. The main channel 18—1 (the equivalent to channel 18 in Figs. 1-6) is shallow and does not run entirely across the block 12, but its end is in abutment with the end of the terminal plate 10 when the terminal screws are in register with the recesses 22 and 24. As in the previously described form protuberances 26 overlie the terminal plate and hold it in position. In Fig. 7 the terminal plate can be slid into place in one direction only, but it automatically positions itself without the necessity of the screw 14 being turned into the plate any particular distance. In Fig. 7 the block 12 is recessed transversely entirely across the block from its top surface forming a subsurface 13 preferably in the same plane as of the upper surface of the terminal plate 10.

It will be obvious to those skilled in the art that many other modifications within the scope of this invention may be made without departing from the spirit of the invention. By way of example and not by way of limitation, it may be mentioned that the sub-channel 20 may be omitted and sliding movement of the terminal plate 10 out of the channel 18 may be prevented by the shank of the terminal screws taking directly into bores such as 22 and 24, which are bored directly in the bottom of the channel 18. An advantage of the sub-channel 20 is that the terminal plate 10 may be slid into position and it will automatically stop when the terminal screw comes in register with the bore 24. In that manner the delicate operation of moving the terminal plate 10 backward and forward until the terminal

screws are in direct register with the bores 22 and 24 is obviated. This same advantage is accomplished in another way in the form shown in Fig. 7.

Another example of a change in form of the structure without departing from the scope of the invention would be narrowing of the channel 18 and widening of the terminal plate 10 or increasing the size of the extensions 10a and 10b so as to fit in lateral grooves which might be cut into the walls of the channel 18 adjacent the floor of the channel. Other modifications will occur to those skilled in the art. Therefore I do not limit myself to the specific forms of the invention shown and described, but as my invention, I claim:

1. An electric wire terminal device comprising an insulating block having an open and uncovered channel extending across a face thereof, a metallic terminal plate non-permanently seated in said channel, a terminal screw comprising a head and a threaded end, said end threaded into said plate and adapted to extend therethrough, said channel having a recess adapted to receive said end to prevent planar movement of said plate into or out of said channel, protuberances from the opposite walls of said channel overlying portions of said plate to prevent movement of said plate from the channel in a direction perpendicular to the floor of the channel, the distance between said protuberances being greater than the diameters of the head and threaded end of said terminal screw, whereby said plate with the terminal screw attached may be moved into said channel and into a position where said terminal screw is in register with said recess, said terminal screw passing between said protuberances during such movement.

2. An electric terminal device comprising an insulating block having a main channel therein, a sub-channel in the floor of the main channel and extending a portion of the length of the main channel, a metallic terminal plate located in said main channel, a terminal screw threaded into said plate and adapted to have its end extend through said plate, said sub-channel accommodating said screw end upon movement of said plate into said main channel, said sub-channel having a recess adapted to receive said screw end to hold said plate against planar movement outwardly of the channel, said screw end abutting the end of said sub-channel when in register with said recess, and means engaging the surface of said plate to prevent movement of said plate from said channel in a direction perpendicular to the main channel floor.

3. An electric terminal device comprising an insulating block having a main channel therein, a sub-channel in the floor of the main channel and extending a portion of the length of the main channel, a metallic terminal plate located in said main channel, a terminal screw threaded into said plate and adapted to have its end extend through said plate, said sub-channel accommodating said screw end upon movement of said plate into said main channel, said sub-channel having a recess adapted to receive said screw end to hold said plate against planar movement outwardly of the channel, said screw end abutting the end of said sub-channel when in register with said recess, and protuberances on the walls of said main channel to prevent movement of said plate from said channel in a direction perpendicular to the main channel floor.
